UNITED STATES PATENT OFFICE.

ADAM J. GEHRING, OF GARDENVILLE, MARYLAND.

WOOD-SCREW.

1,184,173.

Specification of Letters Patent. Patented May 23, 1916.

Application filed February 12, 1916. Serial No. 77,944.

To all whom it may concern:

Be it known that I, ADAM J. GEHRING, a citizen of the United States, residing at Gardenville, in the county of Baltimore and State of Maryland, have invented certain new and useful Improvements in Wood-Screws; and I do declare the following to be a full, clear, and exact description of the invention, such as will enable others skilled in the art to which it appertains to make and use the same.

My invention relates to improvements in wood screws and has for one object to provide a device of this class which when driven will present an entirely flat surface without any cavities or incisions in which dirt or other matter may lodge, the appearance being therefore much more sightly than that of the usual type of screw employing a transverse kerf.

Another object of the invention is to form the screw head with a pair of parallel bores to receive projecting pins on a screw driver when driving or removing the screw, and to so locate and form said bores as to allow them to also receive a pair of locking pins to be used for preventing rotation of the screw after the latter is driven, said bores being also so located as to allow these pins to be driven therefrom into the work when the screw is to be removed.

With the foregoing objects in view, the invention consists of certain novel features of construction and unique combinations of parts to be hereinafter fully described and claimed, the descriptive matter being supplemented by the accompanying drawing which constitutes a part of this application and in which:

Figure 1 is a side elevation of a screw constructed in accordance with the invention, showing the same locked in operative position; Fig. 2 is a similar view with parts broken away and in section; Fig. 3 is an end elevation of the screw applied; Fig. 4 is a view similar to Fig. 1 showing the locking pins driven from the bores to allow the screw to be removed; Fig. 5 is a side elevation partly in section showing the manner in which the improved screw is locked against rotation when passing through a metallic plate; Fig. 6 is a fragmentary plan view of such a plate; and Fig. 7 is a sectional view thereof taken on the plane of the line 7-7 of Fig. 6.

In Figs. 1 to 4 of the drawings, the nu-

meral 1 designates an externally threaded screw shank equipped with the usual frusto cone-shaped head 2 having a flat outer end, the inner end of this head being preferably serrated as shown at 3 in order that it may serve as a file to form a countersink in the wood or the like W into which the screw is driven.

Formed longitudinally through the head 2 and opening through the inner and outer ends thereof, are two bores 4 of equal diameter throughout their lengths, the innermost sides of these bores being flush with the exterior of the shank 1 as depicted most clearly in Fig. 2. When driving the screw, a pair of projecting pins on a suitable screw driver will be received in the bores 4 to serve as rotating means for the screw, but after the latter has been driven, the bores in question are adapted to receive therein a pair of locking pins 5 of equal diameter throughout their lengths. The pins 5 are of a size to completely fill the bores 4 and are provided with flat outer ends which lie flush with the flat outer end of the head 2, thus presenting no shoulders or the like against which matter of any kind might accumulate. The inner ends of the pins 5 project beyond the head 2 into the work as clearly shown in Fig. 2, these ends being preferably pointed as shown. Thus, the pins in question will readily prevent rotation of the screw.

In order to allow the screw to be withdrawn when desired, the pins 5 will be driven entirely through the bores 4 as shown in Fig. 4, this being done by the projecting pins on the screw driver above referred to or by the use of a suitable punch. The screw may now be rotated in the necessary manner to allow it to be withdrawn. An important feature of the invention resides in the fact that both pins may now be recovered from the screw hole, these pins remaining intact and therefore being fit for further use.

In Figs. 5, 6 and 7 a screw 1^a is shown identical in construction with that above described with the exception that its head is formed with no serrations, this type of screw being adapted for fastening a metal plate or the like P to another body such as that indicated at B. When this is to be done, the plate P will be formed with a counter-sunk opening 10 and will have an arcuate series 105 of notches 11 opening into such opening. By the means above described, the screw will

now be driven through the opening 10 into the body B and the head of said screw will be received in the opening in question. Pins 5^a will now be driven through the bores of 5 the screw head and through the notches 11 into said body B. Obviously, this arrangement will prevent rotation and removal of the screw until the pins are driven beyond the bores of the screw head in the manner 10 hereinbefore set forth.

From the foregoing, it will be understood that although the improved screw is of extremely simple and inexpensive formation, it will be highly efficient and durable. I am 15 aware that screws have heretofore been used having heads with bores extending therefrom, but in so far as I am advised, the exact arrangement of these bores shown in the accompanying drawings has not heretofore existed. This arrangement possesses 20 advantages over the previous state of the art with which I am familiar in that said bores serve as means for receiving a screw driver to drive or remove the screw, as means for 25 receiving locking pins and for allowing said pins to be easily driven therefrom, and lastly for allowing these pins to be recovered.

It will be noted that my improved screw has a further advantage over the ordinary 30 screw with the screw driver notch in that such old style screws when used in the floor are quickly worn down so that the screw driver notch is entirely worn away and in such case, it is almost impossible to remove 35 the screw without mutilating the floor. With respect to the screw described herein, it will be seen that the wrench and pin receiving apertures 4 are extremely deep so that the head will never be worn sufficiently 40 to prevent the application of the screw driver or wrench used to remove the screw.

I claim:-

1. A wood screw comprising a threaded shank having a circular head with a flat 45 outer end, said head being formed with a pair of cylindrical bores of equal diameter throughout their lengths lying parallel to the axis of the shank and opening through the inner and outer ends of said head, the 50 innermost sides of the bores lying flush with

the exterior of the shank, said bores being adapted to receive a pair of projecting pins on a screw driver for driving or removing the screw, and to receive locking pins.

2. A wood screw comprising a threaded shank having a circular head with a flat outer end, said head being formed with a pair of cylindrical bores of equal diameter throughout their lengths lying parallel to the axis of the shank and opening through 60 the inner and outer ends of said head, the innermost sides of the bores lying flush with the exterior of the shank, said bores being adapted to receive a pair of projecting pins on a screw driver for driving or removing 65 the screw; in combination with a pair of cylindrical pins of equal diameter throughout their lengths to be driven into said bores and to project beyond the inner ends thereof to lock the screw against movement after 70 being driven, said pins being also adapted to be driven entirely through said bores when the screw is to be removed.

3. A wood screw comprising a threaded shank having a circular head with a flat 75 outer end, said head being formed with a pair of cylindrical bores of equal diameter throughout their lengths lying parallel to the axis of the shank and opening through the inner and outer ends of said head, the innermost sides of the bores lying flush with the exterior of the shank, said bores being adapted to receive a pair of projecting pins on a screw driver for driving or removing 80 the screw; in combination with a metallic 85 plate having a countersunk opening to receive the head of the screw and having notches communicating with said opening, and a pair of pins to be driven through the aforesaid bores into the notches to lock the 90 screw against rotation, said pins being also adapted to be driven entirely from said bores to allow rotation of the screw.

In testimony whereof I have hereunto set my hand in presence of two subscribing 95 witnesses.

ADAM J. GEHRING.
